CLAIM

The ornamental design for an electric towel rack, as shown and described.

DESCRIPTION

FIG. 1 is a front elevational view of an electric towel rack showing my new design;

FIG. 2 is a right end elevational view thereof;

FIG. 3 is a rear elevational view thereof;

FIG. 4 is a left end elevational view thereof;

FIG. 5 is a bottom plan view thereof; and

FIG. 6 is a top plan view thereof.

The electrical cord element is shown broken-away to indicate indeterminate length.

FIG. 5FIG. 2FIG. 1FIG. 6FIG. 4FIG. 3
